UNITED STATES PATENT OFFICE.

JOHN O. McKEAN, OF WESTFIELD, MASSACHUSETTS, ASSIGNOR TO FOSTER MACHINE COMPANY, OF WESTFIELD, MASSACHUSETTS, A CORPORATION OF MASSACHUSETTS.

AUTOMATIC STARTER FOR WINDING-MACHINE STOP MOTIONS.

Application filed May 2, 1924. Serial No. 710,609.

To all whom it may concern:

Be it known that I, JOHN O. McKEAN, a citizen of the United States, and resident of Westfield, in the county of Hampden and 5 State of Massachusetts, have invented a new and useful Improvement in Automatic Starters for Winding-Machine Stop Motions, of which the following is a specification.

The object of my invention is to provide 10 manually controlled means acting through a portion of the stop motion mechanism to automatically start the winding of the cop.

My invention is shown in connection with a winding machine for yarn, etc., having a 15 stop motion mechanism of the type illustrated in United States Letters Patent to me, No. 952,015, dated March 15th, 1910 and to Holt & Kershaw No. 1,353,475, dated September 21st, 1920, in which the rocking 20 movement of the stop motion plate lever controls the stopping and starting of the winding of the cop.

A practical embodiment of my invention is represented in the accompanying drawings, in which 25

Fig. 1 represents in vertical cross section so much of a winding machine as includes my invention, the parts being shown in their "running" position.

Fig. 2 represents a similar view with the parts shown in their "stop" position.

Fig. 3 represents a similar view with the parts in the positions they assume when the starting hand lever has been manually 35 rocked inwardly, to bring its pawl into the path of the starting kicker.

Fig. 4 represents a detail section in another plane, with the parts in the positions shown in Fig. 3.

I will first describe, generally, the parts 40 of the winding machine and stop motion which are necessary to give a clear understanding of my automatic starter.

The stop motion plate lever 1 is pivoted at 45 2, to the auxiliary frame 3, uprising from the rail 4. The plate lever is yieldingly held in either of its two positions by the usual spring 5. The continuously rotating cop driving roll 6 is mounted in the auxiliary frame 3. The cop holder 7 is pivoted at 50 8 to the main frame 9 and it is provided with the depending rock arm 10 connected at its lower end to the toothed operating handle

bar 11. The uprising arm 12 of the plate lever 1 is engaged, as usual, by the handle 55 bar 11.

The cross shaft 13 is mounted in the lower arm of the plate lever 1, on which shaft the drop wire lever is loosely pivoted, the drop wire itself being denoted by 14 and its depending hook arm by 15. This hook arm 15 is dropped, as usual, into the path of the stop kicker 16, carried by the continuously 60 oscillating kicker shaft 17, when the thread breaks or is exhausted, thereby causing the kicker 16 to rock the plate lever 1 in a direction to raise the cop 7 away from its contact with the driving roll 6 and thus stop the winding of the cop.

The kicker shaft 17 is continuously oscillated from the shaft 18 through the pitman 19 which connects the shaft crank 20 with the arm 21, which depends from the shaft 17.

The yarn, or the like, is led through the slab catcher and tension device 22, the drop wire 14 and over the guide bar 23, to the cop.

The manually controlled means acting through a portion of the stop motion mechanism for automatically starting the winding of the cop is constructed, arranged and operated as follows:

A starting hand lever 24 is loosely pivoted on the shaft 13, carried by the plate lever 1, which hand lever tends, by gravity, to swing to the limit of its outward movement, away 85 from the plate lever.

A starting kicker 25 is carried by the continuously oscillating shaft 17 in a different plane from that of the stop kicker 16. A pawl 26 is pivoted on the starting hand lever 24 in position to be moved into the path of the starting kicker 25 when the starting hand lever 24 is moved to the limit of its inward movement toward the plate lever 1 and the plate lever is at the limit of its inward movement.

As the starting hand lever 24 tends, by gravity, to swing outwardly away from the stop motion plate lever 1, and to thereby lift the pawl 26 out of the path of the oscillating starting kicker 25, I provide a latch 27, pivoted at 28 to the hand lever for temporarily locking the hand lever at the limit of its inward movement with the pawl in the path of the starting kicker. This is accomplished by causing the free end of the

said latch to rest upon the oscillating kicker shaft until it is disengaged therefrom. My automatic starting mechanism is placed in operation as follows:

5 I will assume that the stop motion plate lever 1 has been rocked from its "run" position, shown in Fig. 1 to its "stop" position, shown in Fig. 2.

10 After the yarn, or the like, is ready for winding, the starting hand lever 24 is manually rocked inwardly toward the stop motion plate lever 1 until the pawl 26 has been moved into the path of the starting kicker 25 and until the latch 27 has been brought 15 into engagement with the oscillating kicker shaft 17. The latch will then temporarily hold the parts in this position. If the pawl happened to be brought into the path of the starting kicker in back of the kicker, the 20 pawl will ride over the kicker as the kicker moves rearwardly and then dropped into position in front of the kicker. The kicker, in its forward movement, will engage the pawl and through it, rock the stop motion plate 25 lever and the parts carried thereby, to the limit of the outward movement of the plate lever where it will be yieldingly held by the spring 5. This movement will permit the cop holder 7 to drop the cop into engagement with the driving roll 6 and thus start the winding of the cop. This outward movement of the stop motion plate lever will release the latch 27 from its engagement with the continuously oscillating kicker shaft 17, 30 thereby permitting the starting hand lever 24 to drop, by gravity, to the limit of its outward movement, thus raising the pawl 26 out of the path of the oscillating starting kicker 25.

40 It is evident that various changes may be resorted to in the construction, form and arrangement of the several parts without departing from the spirit and scope of my invention; hence, I do not intend to be limited to the particular embodiment herein shown and described, but what I claim is:—

45 1. A winding machine stop motion including the kicker shaft, and a manually controlled automatic starter comprising a starting kicker on said shaft, and means arranged to be moved into the path of the kicker.

50 2. A winding machine stop motion including the kicker shaft and the plate lever operated thereby, and a manually controlled automatic starter comprising a starting kicker on said shaft, and means mounted on said plate lever, arranged to be moved into the path of the kicker.

55 3. A winding machine stop motion including the kicker shaft and the plate lever operated thereby, and a manually controlled automatic starter also operated by said kicker shaft, comprising a kicker on said shaft, and a hand lever mounted on said

lever, said hand lever having an element arranged to be moved into the path of the said kicker.

4. A winding machine stop motion including the kicker shaft and the plate lever operated thereby, and a manually controlled automatic starter also operated by said kicker shaft, comprising a kicker on said shaft, a hand lever mounted on said lever, said hand lever having an element arranged to be moved into the path of the said kicker, and a device carried by the hand lever for temporarily locking the lever with said element in the path of the said kicker.

5. A winding machine stop motion including the kicker shaft and the plate lever operated thereby, and a manually controlled automatic starter also operated by said kicker shaft, comprising a kicker on said shaft, a hand lever mounted on said lever, said hand lever having an element arranged to be moved into the path of the said kicker, and a device carried by the hand lever for temporarily locking the lever with said element in the path of the said kicker, said device being automatically released by the forward movement of the said kicker.

6. A winding machine stop motion including the kicker shaft and the plate lever operated thereby, and a manually controlled automatic starter also operated by said kicker shaft, comprising a kicker on said shaft, and a hand lever mounted on said plate lever, said hand lever having a pawl arranged to be moved into the path of the said kicker.

7. A winding machine stop motion including the kicker shaft and the plate lever operated thereby, and a manually controlled automatic starter also operated by said kicker shaft, comprising a kicker on said shaft, a hand lever mounted on said plate lever, said hand lever having a pawl arranged to be moved into the path of the said kicker, and a latch carried by said hand lever, arranged to be brought into engagement with said shaft, for temporarily locking the lever with said pawl in the path of the said kicker.

8. A winding machine stop motion including the kicker shaft and the plate lever operated thereby, and a manually controlled automatic starter also operated by said kicker shaft, comprising a kicker on said shaft, a hand lever mounted on said plate lever, said hand lever having a pawl arranged to be moved into the path of the said kicker, and a latch carried by said hand lever arranged to be brought into engagement with said shaft, for temporarily locking the lever with said pawl in the path of the said kicker, said latch being automatically released by the forward movement of said kicker.

9. A winding machine stop motion includ-

ing the kicker shaft and the plate lever operated thereby and a manually controlled automatic starter also operated by said kicker shaft, comprising a kicker on said shaft, a hand lever mounted on said plate lever, said hand lever having a pawl arranged to be moved into the path of the said kicker, a latch carried by said hand lever arranged to be brought into engagement with said shaft, for temporarily locking the lever with the pawl in the path of the said kicker, said latch being automatically released by the forward movement of the said kicker.

5. A winding machine stop motion including the kicker shaft and the plate lever operated thereby, and a manually controlled automatic starter also operated by said kicker shaft, comprising a kicker on said shaft, a hand lever pivoted on said plate lever arranged to be moved by said hand lever into the path of the said kicker, a latch carried by the said hand lever, arranged to be brought into engagement with the said shaft, for temporarily locking the lever with the pawl in the path of the said kicker, said latch being automatically released by the forward movement of the said kicker, and said hand lever being operated, by gravity, when released, to automatically rock into its non-starting position.

10. A winding machine stop motion including the kicker shaft and the plate lever operated thereby, and a manually controlled automatic starter also operated by said kicker shaft, comprising a kicker on said shaft, a hand lever pivoted on said plate lever provided with a pawl arranged to be moved by said hand lever into the path of the said kicker, and a latch carried by the said hand lever, arranged to be brought into engagement with the said shaft, for temporarily locking the lever with the pawl in the path of the said kicker, said latch being automatically released by the forward movement of the said kicker, and said hand lever being operated, by gravity, when released, to automatically rock into its non-starting position.

15. A winding machine stop motion including the kicker shaft and the plate lever operated thereby, and a manually controlled automatic starter also operated by said kicker shaft, comprising a kicker on said shaft, a hand lever pivoted on said plate lever provided with a pawl arranged to be moved by said hand lever into the path of the said kicker, and a latch carried by the said hand lever, arranged to be brought into engagement with the said shaft, for temporarily locking the lever with the pawl in the path of the said kicker, said latch being automatically released by the forward movement of the said kicker, and said hand lever being operated, by gravity, when released, to automatically rock into its non-starting position.

In testimony, that I claim the foregoing as my invention, I have signed my name this 29th day of April 1924.

JOHN O. McKEAN.
